UNITED STATES PATENT OFFICE.

VINCENT J. McNAMARA, OF NEW YORK, N. Y.

FOUNTAIN SHAVING BRUSH.

1,417,082.

Specification of Letters Patent. Patented May 23, 1922.

Application filed November 1, 1921. Serial No. 512,027.

To all whom it may concern:

Be it known that I, VINCENT J. McNAMARA, a citizen of the United States, residing at New York, in the county of New York, 5 State of New York, have invented a new and useful Fountain Shaving Brush; and I do hereby declare the following to be a full, clear, and exact description of the invention, such as will enable others skilled in the art to 10 which it appertains to make and use the same.

The invention relates to fountain shaving brushes, and has for its object to provide a device of this character comprising a chambered handle for the reception of a collapsible tube of shaving soap, a plunger in said handle for collapsing said tube and to provide the handle member with a removable bristle carrying member having a soap passage 15 therein, into which soap is forced from the collapsible tube.

A further object is to provide the removable brush carrying member with a tube forming the soap passage into the brush, 20 said tube being provided with a pliable tip, which prevents the tube from coming into engagement with the face during a lathering operation.

With the above and other objects in view 30 the invention resides in the combination and arrangement of parts as hereinafter set forth, shown in the drawings, described and claimed, it being understood that changes in the precise embodiment of the invention 35 may be made within the scope of what is claimed without departing from the spirit of the invention.

In the drawings: —

Figure 1 is a vertical sectional view 40 through the brush.

Figure 2 is a bottom plan view of the chambered handle, showing the collapsible soap tube therein.

Figure 3 is a top plan view of the lower 45 removable portion of the handle, showing the brush carrying member therein.

Figure 4 is an enlarged detail sectional view through the lower end of the soap passage 2 carried by the brush and through 50 the nipple formed from pliable material.

Referring to the drawings, the numeral 1 designates the handle of the fountain brush, which handle comprises the upper section 2 having the cylindrical chamber 3 55 therein and a lower section 4, which is threaded at 6 on the lower end of the section

2 of the handle. Disposed within the chamber 3 of the handle section 2 is a plunger 5, which plunger is adapted to be forced inwardly for collapsing the collapsible soap 60 carrying tube 7, which may be of any conventional form. If so desired the upper end of the plunger 5 may be provided with a member 8, by means of which member the brush when not in use may be suspended 65 from a suitable support for drying and draining purposes. Interposed between the adjacent ends of the handle sections 2 and 4 is a washer 9 preferably formed from resilient material, which washer prevents entrance 70 of water to the chamber 3 during a shaving operation.

The lower end of the collapsible tube 7 is provided with a flanged discharge neck 10 which is threaded at 11 into the disc 12. The 75 disc 12 is in turn threaded at 13 on the upper end of a discharge tube 14, which tube extends through the butt end 15 of the brush 14^a and is imbedded in said butt end, and held therein by the close engagement of the 80 butt ends of the bristles, which is encased in the annular sleeve 16. Annular sleeve 16 is disposed within an annular recess 17 in the removable lower end section 4 of the handle member and rests upon the flange 18. The 85 disc 12 is disposed within the upper end of the chamber 17 and rests upon an annular shoulder 19, and is held against downward displacement by said shoulder 19 and against upward displacement by the engagement of the lower face 20 of the brush handle section 2 with the upper face of the disc 12. The lower end of the discharge tube 14 extends below the lower end of the removable 90 section 4 and is provided with a flexible and pliable nipple 21, through which the soap from the collapsible tube 7 is discharged. The nipple 21 forms means for preventing 95 injury to the face of the user of the brush during a lathering operation.

After the contents of the tube 7 have been consumed, a new tube 7 is placed in the chamber 3 by simply removing the handle section 4 and unscrewing the old collapsed tube 7 from the disc 12 and replacing the same with a new tube, after which the handle section 4 is again screwed on the lower end of the handle section 2.

From the above it will be seen that a fountain shaving brush is provided wherein 100 conventional forms of collapsible soap tubes may be placed within the brush and the con-

tents thereof utilized as desired. It will also be seen that a fountain shaving brush is provided which is simple in construction, sanitary and one wherein the parts have been 5 reduced to a minimum.

The invention having been set forth what is claimed as new and useful is:—

1. A shaving brush comprising a handle member, said handle member being provided 10 with a detachable chambered end, a shoulder carried at the lower end of the detachable chambered end, a bristle carrying member disposed on the shoulder of the detachable chambered end of the handle and disposed 15 within the chamber thereof, a disc disposed in the upper end of the chamber of the detachable chambered end of the handle, a soap conducting tube extending downwardly from said disc and terminating in the bristles of the brush, a resilient member carried by said tube, a plunger slidably mounted in a chamber of the handle member, and means 20 whereby a collapsible soap tube may be supported on the disc with its discharge opening 25 in registration with the tube carried by

the disc and in registration with the plunger.

2. A shaving brush comprising a handle member having a chamber therein, a removable bristle carrying end carried by said handle, a disc interposed between the bristle carrying end and the handle member, a discharge tube extending downwardly from the disc into the bristles of the brush carried by the removable brush carrying end, a resilient member carried by the end of the discharge tube, a plunger disposed within the chamber of the handle member, a threaded opening carried by the disc in registration with the discharge tube and forming means 35 whereby the collapsible soap tube may be supported in the chamber of the handle member beneath the plunger.

In testimony whereof I have signed my name to this specification in the presence of 45 two subscribing witnesses.

VINCENT J. McNAMARA.
